UNITED STATES PATENT OFFICE

149,910

DESIGN FOR A BOOK DISPLAY RACK

Ralph F. Schuster, San Antonio, Tex.

Application May 2, 1947, Serial No. 138,774

Term of patent 14 years

(Cl. D30—9)

To all whom it may concern:

Be it known that I, Ralph F. Schuster, a citizen of the United States, residing at San Antonio, in the county of Bexar and State of Texas, have invented a new, original, and ornamental Design for a Book Display Rack, of which the following is a specification, reference being had to the accompanying drawings, forming part thereof.

Fig. 1 is a side elevational view of a book display rack showing my new design, the opposite side is similar.

Fig. 2 is an end elevational view, the opposite end is similar.

Fig. 3 is a top plan view thereof.

Fig. 4 is a top perspective view of the rack.

I claim:

The ornamental design for a book display rack as shown.

RALPH F. SCHUSTER.
